UNITED STATES PATENT OFFICE.

WILLIAM OLIVER ASHE, OF YONKERS, NEW YORK, ASSIGNOR TO NATHAN MANUFACTURING COMPANY, OF NEW YORK, N. Y., A CORPORATION OF NEW YORK.

WATER COLUMN.

Original application filed June 16, 1921, Serial No. 477,872. Divided and this application filed September 14, 1922. Serial No. 588,282.

To all whom it may concern:

Be it known that I, WILLIAM OLIVER ASHE, a citizen of the United States, residing at the city of Yonkers, in the county of 5 Westchester and State of New York, have invented certain new and useful Improvements in a Water Column, of which the following is a specification.

My invention relates to water columns, 10 and more particularly to the adaptation and arrangement of parts in connection therewith, as will be more fully hereinafter pointed out.

This application is a division of my application Serial No. 477,872, filed in the 15 United States Patent Office June 16, 1921.

Serious problems have arisen in engine practice in relation to determining the correct indication of the height of water in the 20 boiler over the crown sheet, which is the top of the fire box. Neither the water gage nor the gage cock of ordinary locomotive practice correctly indicates the desired height of water over the crown sheet. The height of 25 water as indicated by both the water gage and gage cock is more particularly at fault during the period when the locomotive is in operation with the throttle valve of the engine open.

It has been determined by exhaustive investigation of this subject by the Federal boiler inspection service that in a locomotive boiler which usually has a sloping back head there is a very severe circulation in the back 30 head of the boiler when the locomotive is in operation with the throttle valve of the engine open. This investigation disclosed that often while the locomotive is in operation with the throttle valve of the engine 35 open the water gage and also all three gage cocks indicate that the water in the boiler is above the height required, whereas on stopping the locomotive it has been determined that with the locomotive at rest the 40 actual height of water in the boiler was far below the amount required for the safety 45 of both the boiler and of the crown sheet.

This false indication in both the water gage and gage cock of usual locomotive 50 practice often leads not only to the damage of the crown sheet, but has in many instances been a contributing factor in boiler explosions.

My invention overcomes these difficulties

and unnecessary hazards of the present locomotive and engine practice, and enables the operator or engineer to at all times and under all conditions know the correct height of the water in the boiler over the crown sheet.

The fact has definitely been determined that gage cocks and gage glasses screwed directly to the boiler do not correctly indicate the general water level, and that in order to make them give a correct indication of the water level it is necessary to apply an intermediate device between the boiler and the gage cock and gage glass, which is the water column. This consists practically of a long cylinder of proper diameter with top and bottom connections to the steam space and water space of the boiler, and is provided with proper means for attaching to said column gage cocks and a water gage.

There is very little available space on the back head of a locomotive, as there are so many necessary appliances located there in order that they may be within easy reach and sight of the engineer at all times. The available space for application of the water column is also greatly restricted by the main throttle lever. The application of two water glasses, one of which is applied to the water column on the right hand side of the back head, further restricts the back head space. It has therefore been necessary, in order to make my device practical in locomotive practice, to so construct the water column that it will lie close to the boiler head its entire length and particularly at 50 its lower extremity where the space available is most limited, and I have so devised it with the lower portion having a substantially reduced cross section. It is also necessary in locomotive practice that the handles 55 of the valves of the gage cocks and of the water gage should lie as close as possible to the valves, as otherwise they will interfere with the other appliances. I have solved both of these problems.

Referring to the drawings, Figure 1 is a front view of my device; Fig. 2 is a side view of the water column as shown in Figure 1, but with a portion of the lower end broken away; Fig. 3 is a top plan view of Fig. 2; Fig. 4 is a fragmentary cross-section on the line 4-4 of Fig. 2, part of which is broken away for convenience; Fig. 5 is a

cross-section on the line 5—5 of Fig. 2; Fig. 6 is a side view of one embodiment of my device showing the sloping back head of the usual locomotive boiler in dotted outline 5 and with the connections broken away; Fig. 7 is a front view of the device shown in Fig. 6 as seen facing the back head of the boiler and Fig. 8 is a vertical section showing the manner of mounting the gage 10 cock in the water column.

In the drawings 6 is the main body of the water column to which are cast integrally three necks 7, having external left hand threads 8, and on which are adapted to 15 be mounted three gage cocks which are not shown.

The body 6 also has integrally cast thereto a bracket 9 which is adapted to be bolted to the boiler head. Another bracket, which 20 is not shown, is also integrally cast to the body 6, to which is adapted to be rigidly secured a dripper of normal construction not shown, and which is adapted to catch water and steam from the gage cocks. At 25 the upper end of the body 6 is a neck 11 having an external thread 12, which is adapted to be connected to the top of the boiler head or steam head by a pipe in the usual manner. Connection is also made to 30 the lower or water containing part of the boiler head at the bottom of the body 6 by means of a threaded boring 13, into which a pipe is adapted to be threaded in the usual way, connecting the body of the 35 water column thereto.

The body 6 also has integrally cast therein necks 14 and 15, both of which are internally threaded, and into which by means of usual pipe connections is adapted to be 40 secured a water gage which is not shown.

The gage cocks have external threads adapted to engage internal threads 16 in the necks 7, which also have tapered valve seats 17 adapted to seat the valve of said gage 45 cocks. It should be noted that by placing the valve seat 17 in the body of the column 6 and that by arranging the gage cocks so that they are secured directly to the necks 17 of the column 6, a very material saving in 50 the extension of the gage cock from the body of the column 6 is effected. This effects a very material saving in the very restricted space available in the cab of the locomotive.

55 In the operation of the water column the water will circulate freely from the boiler boring 13 and the connections thence through the body 6 until it finds its level. Steam will enter the water column body 6 60 through the boring 12 and connections from the steam head of the boiler. This steam will cause a downward pressure on the water in both the body 6 and the water gage connected thereto and thereby correct the water 65 level in the water gage and gage cocks se-

cured to necks 7. It is thus seen that the water in coming from the boiler is received directly into the water column body 6 before it passes into the water gage, and has an opportunity to become stabilized as to its level in the body 6, thereby correcting said water level before it is indicated in the water gage or the gage cocks secured to necks 7.

The lower portion of body 6 is made with a flattened portion 18 in which suitably threaded borings similar to 13 can be made at the point in said flattened portion 18, where it is desired to make connection to the water head of the boiler. A boring 19 is arranged in alignment with boring 13 to facilitate cleaning this lower connection to the boiler. A drain neck connection 20 for the body 6 is made integral with the body 6 and 20 has an internal threading 21.

In Figs. 6, 7 and 8 the main body 6 of the water column has cast integrally therewith three necks 7 having external left hand threads 8, and on which are adapted to be mounted three gage cocks 22 by means of 90 coupling nuts 23 which are internally threaded at 24 with the left hand thread adapted to engage the left hand thread 8.

The body 6 also has integrally cast thereto a bracket 9 which is adapted to be bolted by means of bolt 25 to bracket 26 which is rigidly secured to the boiler head. Another bracket 27 is also integrally cast to the body 6 to which is adapted to be rigidly secured a dripper of usual construction (not 95 shown) which is adapted to catch water and steam from the gage cocks 22. At the upper end of the body 6 is a neck 11 having an external thread 12 to which connection is made by union coupling 28 having an internal thread and thereby connecting the same to a pipe 29, which at its opposite end is connected to the top of the boiler head or steam head. Connection is also made to the lower or water containing part of the boiler head at the bottom of the body 6 by means of a threaded boring 13 into which a pipe 30 having union coupling 31 is adapted to be threaded, connecting the body of the water column there- 100 to.

The body 6 also has integrally cast therein necks 14 and 15, both of which are internally threaded, and into which by means of union couplings 32 and 33 are secured 105 pipe connections 34 and 35 respectively. The pipes 34 and 35 are connected in the usual manner to a water gage which is not shown.

The gage cocks 22 have bodies 36 which 110 have right hand external threads 37 adapted to engage the right hand internal threads 24 of the coupling nuts 23. A spindle 38 has a left hand threaded lower member 39 terminating in a ball shaped end 40, said 115

threaded member 39 being adapted to engage an internal thread 41 which also has a tapered valve seat 42 adapted to receive the ball shaped end 40.

5 It should be noted that by the placing of the emergency valve seat 42 in the body of the column 6 and that by arranging the gage cock body 36 so that it is secured directly to the neck 7 of the column 6, a 10 very material saving in the extension of the gage cock from the body of the column 6 has been effected. This effects a very material saving in the very restricted space available in the cab of the locomotive.

15 In the operation of the water column as described the water will circulate freely from the boiler through pipe 30, thence through the body 6 until it finds its level. Steam will enter the water column body 20 6 through the pipe 29 and connections from the steam head of the boiler. This steam will cause a downward pressure on the water in the body 6 and thereby correct the water level in the cocks 22. The lower gage 25 cock 22 is on the level which indicates the lowest safety point for water in the boiler. The other two gage cocks 22 will on opening indicate whether the water is at those levels or below. It is thus seen that the 30 water in coming from the boiler is received directly into the water column 6 and has an opportunity to become stabilized as to its level in the body 6 thereby correcting said water level before it is indicated by 35 opening the gage cocks 22.

I claim:

1. A water column having a body constructed so that throughout its length it will lie relatively close to a sloping boiler head while maintaining its vertical position.
2. A water column having a body constructed so that throughout its length it will lie relatively close to a sloping boiler head while maintaining its vertical position and valve seats integral with said body.
3. A water column having a body con-

structed so that throughout its length it will lie relatively close to a sloping boiler head while maintaining its vertical position in combination with gage cocks having valves seating directly in said body.

4. A water column having a body constructed so that throughout its length it will lie relatively close to a sloping boiler head while maintaining its vertical position, gage cock necks integral with said column, valve seats in the base of said necks and gage cock spindles mounted in said necks.

5. A water column having a body constructed so that throughout its length it will lie relatively close to a sloping boiler head while maintaining its vertical position, gage cock necks integral with said body, valve seats in the base of said necks and gage cock spindles mounted in said necks.

6. The combination of a water column having a body constructed so that throughout its length it will lie relatively close to a sloping boiler head, while maintaining its vertical position, necks integral with said body having valve seats in their bases and gage cocks mounted directly in said necks so that the valves in said gage cocks seat in said valve seats.

7. The combination of a water column having a body constructed so that throughout its length it will lie relatively close to a sloping boiler head while maintaining its vertical position, valve seats integral with said body and gage cocks having valves which seat in said valve seats.

8. The combination of a water column having a body constructed so that throughout its length it will lie relatively close to a sloping boiler head while maintaining its vertical position, gage cock necks integral with said body and gage cock spindles mounted directly in said necks.

In testimony whereof I affix my signature.

WILLIAM OLIVER ASHE.
